UNITED STATES PATENT OFFICE.

FREDERICK LANGLEY, OF COHOES, NEW YORK.

WINDOW CLEANER.

Application filed May 7, 1924. Serial No. 711,682.

This invention relates to improvements in apparatus for cleaning windows.

The primary object of this invention is the provision of apparatus which is adapted for the facile and efficient cleaning of windows, particularly plate glass windows such as are used in business establishments, which are difficult to clean with ordinary methods, and which with improved apparatus may be automatically cleaned without the necessity of the operator entering the display compartment to the rear of the window, so that the windows may be daily cleaned in a manner which will not interfere or disturb with fixtures placed near the window.

A further object of this invention is the provision of window cleaning apparatus embodying means for feeding a supply of cleansing liquid in thin film over the window, and improved means for scraping the cleaning liquid together with any foreign matter from the window.

Other objects and advantages of this invention will be apparent during the course of the following detailed description.

In the accompanying drawings, forming a part of this specification, and wherein similar reference characters designate corresponding parts throughout the several views:

Figure 1 is a side elevation of a window, showing the improved cleaning apparatus as used in connection therewith.

Figures 2, 3, 4 and 5 are cross sectional views, taken substantially on their respective lines in Figure 1 of the drawings, showing improved details of the window cleaning apparatus.

In the drawings, wherein for the purpose of illustration is shown only the preferred embodiment of the invention, the letter A may generally designate any improved window structure, which has associated therewith a casing B, and the improved window cleaning apparatus C.

The window A may be of the plate glass variety, and the casing B enclosed in the same may include side stile portions 11; the top beads 12; and sill structure 13. The sill structure 13 of the casing B is preferably novel in so far as this invention is concerned, and to the inside of the window A the sill structure 13 preferably comprises a sheet metal gutter 14, which slopes from the sides of the window toward the center of the window, so that water may drain toward the central point, where a tubular member 15 supplies

a duct or passageway leading from the gutter 14 to a point at the outside of the building in which the window A is provided and as is clearly illustrated in Figure 1 of the drawings. The gutter may be of any non-corrodible material, and not only slopes from the sides of the window toward the central point thereof, but has a downward slope from the rear edge thereof toward the plane of the glass, as is illustrated in Figure 2 of the drawings.

Referring to the improved window cleaning apparatus C the same includes liquid dispensing receptacles 25 and 26 supported upwardly of the window A, at each side thereof, immediately below the bead or top portions 12 of the window casing B, and which receptacles are of novel formation, and adapted to receive a supply of water therein through a pipe 27 which is provided with suitable fittings and discharge openings leading into openings 29 and 30 in the compartments 25 and 26 respectively for the purpose of conveying water or other cleansing liquid into these receptacles.

The receptacles 25 and 26 are of analogous formation, being substantially triangular in formation, including top substantially horizontally positioned walls 32; vertical walls 33 which are adapted to engage against the inner and outer side surfaces of the window A at the top of said window, and including diagonally positioned or inclined walls 36 and 37 which are bent from the outer edges of the horizontal top walls 32 and which are disposed in spaced relation at the lower edges of the vertical wall 33 to provide relatively narrow passageways 39 and 40 at the lower edges of the receptacles 25 and 26, so that water may flow from the compartments 43 and 44 of these receptacles, respectively in thin films onto the outer and inner surfaces of the glass or window for the purpose of loosening dirt and foreign materials therefrom. It is of course understood that each of these receptacles 25 and 26 have end walls, and in fact the pipe apparatus 27 communicates through the end walls, as is illustrated in Figure 4, wherein is also clearly shown the narrow passageways 39 and 40. These passageways of course extend for the entire length of the receptacles.

The improved window cleaning apparatus C furthermore includes means both inside and outside of the window A for engagement therewith to scrape the film of water and foreign material from the surfaces of the

windows. To this end, at the side stile portions 11, and to the outside and to the inside of the window A, guide casings 50 are provided, which are preferably of sheet metal, 5 substantially constructed, and in each of which guide casings 50 an endless belt 51 is positioned, at its upper end engaging about a suitable pulley 52 provided therefor, and at its lower end engaging about a similar pulley 53; the pulleys 52 and 53 being rotatably supported upon shafts 55 and 56 which bear in the side walls of the guide casings 50. It is distinctly understood that a pair of the belts 51 are provided at each side stile 11, 10 one of these belts being to the inside of the window A and the other to the outside. Each of the belts 51 includes a link or stub portion 57, and both at the inside and the outside of the window A a rod 59 pivotally bears at 15 its ends in the link 57 of the belts 51 at their respective sides of the window A, and so that the rods 59 extend parallel with the plane of the window, and in a slightly spaced relation therewith.

20 Each of the rods 59 is provided with a scraping structure adapted to rub downwardly over a side surface of the window A; and to this end includes a box 62 of elongated formation and substantially U-shaped in cross section, and each of which boxes 62 includes a top wall 63, a bottom wall 64, and a rear wall 65, with a compartment facing in the direction of the window A, and in which compartment felt or other water drying material 66 is received so that it projects outwardly of the box in such relation that it may engage the window A, as will be subsequently mentioned. The boxes are supported upon their respective rods 59 by means of substantially J-shaped bracket portions 70, which may be supplied in any desired number, and which are of peculiar construction so that the weights thereof, due to the force of gravity, normally tend to urge the box portions 62 toward the window A, and for this purpose the bracket portions 70 may be of relatively heavy material, having considerable stock thereon. The boxes 62 on the other hand may be made of some relatively light 45 material such as sheet copper or aluminum. At the lower wall of each box 62 a flexible window scraping member 73 may be supported, being secured to the lower wall 64 of its respective box by means of rivets 75 or the like, and which at its forward edge 50 projects so that it will engage the window A as is illustrated in Figure 2 of the drawings. The felt portion 66 of the box 62, and the flexible rubber portion 73 thereof are adapted 55 to engage both the side surfaces of the window A as the belts 51 are rotated. All the belts are rotated synchronously, and to this end it is preferred that the upper rollers or pulleys 52 at each side of the window A be 60 connected by means of shafts 55 which extend

entirely across the window, and a cross belt 78 is provided in engagement with the pulleys both to the inside and to the outside of the windows at the upper part thereof, as is illustrated in Figure 3, so that the belts 51 to the 70 inside and outside of the windows will be driven in the same direction so that the window engaging cleaners at both sides of the window A will move downwardly in the same direction at the same time. A motor 80 may 75 be supplied, preferably being carried by a wall 81 to the inside of the window, which may drive a pulley mounted on one of the shafts 55, by means of a belt 83, for the operation of the improved window cleaning apparatus.

80 It is to be understood that the guide casings 50 are laterally closed in all directions except as to the facing walls thereof, and in which facing walls grooves 90 are provided so that the rods 59 may extend therethrough to permit their travel with the belts 51. The belts 51 are supported in their travel against liability of transverse flexing by means of rollers 92, which are rotatably supported upon 90 cross bolts 93 carried by the side walls of the guide casings 50.

95 Referring to the operation of the improved cleaning apparatus, water is fed in thin films down over the inner and outer surfaces of the window A, by supplying a certain amount of water to the receptacles 25 and 26; the amount of water which is fed to the receptacles being regulated by means of a conveniently disposed valve 95. It is of course 100 understood that the cleaner structures supporting the felt members 66 and the flexible strips 73 travel with the belts 51, and incident to pivoting of the rods 59 upon the belts, the box structures 62 will always hang lowermost 105 in a compact relation. As the box structures are traveling upward during rotation of the belts in the direction in which they travel, and which is indicated by the arrows in Figure 2 of the drawings, as they pass over the 110 topmost portion of their travel the weight of the brackets 70 will throw the box portions 62 toward the surfaces of the window A, until the rubber strips 73 thereof engage the surfaces of the window, providing a frictional 115 contact therewith, and during downward travel on the window the film of water which has been spread over the surfaces of the window, and the felt padding 66 traveling in engagement with the side surfaces of the window A will dry any of the moisture remaining on the window, and thoroughly polish the same, removing any dullness therefrom.

120 From the foregoing description of the operation of this invention it is apparent that a window cleaning structure has been provided which is novel in operation and which is highly practical, being automatic, and not requiring the presence of a person immediately adjacent the window A to efficiently 125 130

perform the cleaning operation for which it is adapted.

Such changes in the shape, size, and arrangement of parts may be made to the form of the invention herein shown and described, as do not depart from the spirit of the invention or scope of the claims.

I claim:

1. In a window cleaner, a pair of guide casings for attachment to one side of the pane of a window at each side edge thereof, each having an endless slot, the endless slots of the guide casings being in facing relation, pulleys in said guide casings, endless belts rotatably mounted in said casings about said pulleys, a rod extending transversely from guide casing to guide casing and at the ends hereof extending into the slots of said guide casings and being connected to the endless belts therein, and means supported by said rod for engaging the facing side of the window to scrape against and cleanse the same during rotation of said belt.

2. In a window cleaning structure of the class described, a pair of endless belts for

support upon a window casing to a side of the plane of the window along the side edges of the window, a transverse bar having its ends connected with said endless belts in pivotal manner to permit pivoting of the same on 30 the belts, a window cleaning element carried by said bar, and weighted arms connected with said bar and depending therefrom for normally urging said cleaning element against said window.

3. In window cleaning apparatus, the combination of a pair of endless belts for support at the opposite sides of a window pane, a bar pivotally supported at its ends by said belts and extending across a face of said window 40 pane, a box, a window pane cleaning element carried by said box, and depending weighted arms connected with said bar and with said box and adapted, incident to the force of gravity, to maintain the cleaning element in engagement with the face of the window pane only during the downward travel of the box along said window pane.
